United States Patent Office

Des. 233,606
Patented Nov. 12, 1974

233,606

SPRAY HEAD

Jack Rauh, Hacienda Heights, Calif., assignor to Modern
Faucet Manufacturing Company, Los Angeles, Calif.

Filed Dec. 8, 1972, Ser. No. 313,604

Term of patent 14 years

Int. Cl. D23—01

U.S. Cl. D23—37

FIG. 1 is a perspective view of a spray head showing my new design.

FIG. 2 is a top plan view thereof.

FIG. 3 is a side view thereof.

FIG. 4 is a bottom plan view thereof.

I claim:

The ornamental design for a spray head, substantially as shown.
